UNITED STATES PATENT OFFICE

2,600,025

MOUTHPIECE DEVICE

John Sage, Flushing, N. Y.

Application March 9, 1948, Serial No. 13,890

6 Claims. (Cl. 128—136)

1

In accordance with the present invention there is provided an improved device for preventing thumb-sucking, nail-biting, tongue-thrusting, or other objectionable mouth habits on the part of individuals, particularly children who are apt to be subject to such habits which require curing or breaking.

The object of the present invention is to provide an improved appliance for the above-indicated purpose, which can be inserted readily into the vestibule of the oral cavity, in front of the teeth or gums, which appliance is comfortable and effectively obstructs the insertion of the fingers into the mouth.

A further object of this invention is to provide an appliance which is made easily, and which is easily adjustable to fit comfortably in the mouth of the wearer.

A still further object of the invention is to provide a simple and cheaply manufactured device which is easily cleaned after each use.

Further objects and advantages of the invention will become apparent as the description proceeds, and the features of novelty will be apparent as the description proceeds.

The invention will be more readily understood by reference to the accompanying drawings, in which

Fig. 1 is a diagrammatic view indicating the device of the invention as in use.

Fig. 2 is a perspective view showing the device in a position ready for use.

Fig. 3 is a view, in elevation of a similar form of the device, the view illustrating a form of the device with the metal frame completely covered.

Fig. 4 is a transverse sectional elevation taken on the line widest transverse portion of Fig. 3.

Fig. 5 is a perspective view of a further modified form of the device, showing the wire means which is designed to prevent tongue-thrusting on the part of the individual.

Fig. 6 is a view similar to Fig. 1, but showing further the modification of Fig. 5, the view illustrating, however, a form of the device including the resilient pads and their attaching means.

Fig. 7 is an enlarged plan view of one of the resilient pads shown in Fig. 6.

Referring more particularly to the drawings, the device of the present invention comprises a thin, flexible brace, which may be a metal frame composed of parallel spaced prongs arranged in pairs 1, 2 and 3, 4 extending outwardly from a central web 5. The prong arms form reinforcing and attachment means for a soft pad or shield 6 by insertion under webs 7 formed integrally with the shield 6. The shield 6 forms the teeth and gum-engaging member of the assembly and forms an interfering shield for preventing introduction of the fingers into the

2

mouth. The metal frame may be covered completely by the shield 6, and when in use, it is adapted to fit into the vestibule of the mouth with the concave surface against the teeth and gums of the subject.

If metal is used as the bar frame, it is made of the order of about 0.01 inch so as to allow for effective manipulation of the device to fit it into the mouth of the user. It is preferable to make the base frame 1 and the shield web 6 separable for cleaning purposes, but this is not necessary when the base frame 1 is encased completely in the web, as in the showing in Figs. 3 and 4, which form also embraces an upper notch 8, which facilitates the adjustability of the device to the vestibule of the oral cavity. Additional wires 9 also may be provided for inhibiting the tongue-thrusting habit, which are adapted to extend through the open bite between the front teeth.

The flexible, soft web 6 projects beyond the periphery of the base, and the ends of the soft web 6 are preferably indented, as indicated at 10 in order to provide enhanced comfort, the resulting end tabs 11 and 12 being adapted to fit snugly against the forward and side portions of the teeth and gums.

The manner of use of the device will be apparent from the drawings. The device is made in various sizes in proportion to the age of the user, as well as to the size of the mouth. Thus it will be seen that the device is inserted in the mouth, the ends tabs 11 and 12 conforming to the upper and lower teeth and gums and held in place by its fit between the upper and lower gums and cheeks.

The reinforcing base of the device may be made of materials other than of metal, such as plastics, or other reinforcing material possessing the requisite flexibility for the intended purpose.

In the modification shown in Figs. 5, 6 and 7, there is shown a form of the device which is to be used for the correction and therapy of undeveloped lips. In using the device, the patient is given exercises which are to be prescribed, individually and specifically, by a physician. The modification shown in Figs. 6 and 7 may be used for the treatment of abnormal deep mental sulcus of the lower lip, and also for a short non-functioning upper lip.

This modification shown in Figs. 6 and 7 is generally similar to the form of the device described above. However, in the form of the device shown in Figs. 6 and 7, the metal frame 55 is completely covered by the resilient shield 6, and snap fasteners 13 and 13a are provided extending through the shield and integrally secured to said frame. These fasteners are formed to be received in slots 14 and 14a provided in the 60 respective resilient pads 15 and 15a that are

spaced in vertical alignment on the central portion of the device, as shown in Fig. 6. Said fasteners are adapted to detachably hold the pads in position and against accidental displacement, and may be varied as to size and configuration in accordance with particular operating requirements.

It will be apparent therefore, that the details of the device may be varied in accordance with the particular manner of use without departing from the spirit of the invention; and it will be apparent that various structural modifications may be made without departing from the scope of the invention as may be necessary to adapt it to varying conditions and uses, as defined in the appended claims.

What is claimed is:

1. A dental device adapted to be inserted into the vestibule of an oral cavity and to engage the teeth and gums of a wearer, which comprises a flexible frame including a central solid web portion and spaced finger-like projections extending oppositely from the central web portion, a soft, resilient pad mounted on the flexible frame adapted to engage and overlie the teeth and gums of the wearer, the said pad extending peripherally beyond all peripheral portions of the frame member, the frame member and resilient pad being adapted to be adjusted in contour to the shape of the mouth of the wearer, the solid web portion and the finger-like portions of the flexible frame preventing insertion of a finger into the mouth of the wearer of the device, and means extending inwardly from the pad for preventing tongue-protrusion of the wearer, the said means extending through the open bite between the teeth of the wearer.

2. A dental device adapted to be inserted into the vestibule of an oral cavity and to engage the teeth and gums of a wearer, which device comprises a flexible frame including a central solid web portion and spaced pairs of finger-like projections oppositely extending from the guard web, a layer of soft pliable material mounted on the frame and covering one side of the frame that forms the inner side of the frame when in use, pairs of snap fastening means on the opposite side of the frame secured thereto one above another, a resilient pad secured to each pair of fastening means and adapted to engage the lips when the device is in service, and means in the resilient pads for preventing displacement of the pads from the fastening means.

3. A dental device adapted to be inserted into the vestibule of an oral cavity and to engage the teeth and gums of a wearer, which device comprises a flexible frame including a central solid web portion and spaced pairs of finger-like projections oppositely extending from the guard web, a layer of soft pliable material mounted on the frame and covering one side of the frame that forms the inner side of the frame when in use, pairs of snap-fastening means on the opposite side of the frame secured thereto one above another, a resilient pad secured to each pair of fastening means and adapted to engage the lips when the device is in service, and slots in the resilient pads adapted to receive the fastening means and to fit thereover for preventing displacement of the pads from the fastening means.

4. A dental device adapted to be inserted into the vestibule of an oral cavity and to engage the teeth and gums of a wearer and to be re-

tained in position by pressure between the cheeks and upper and lower gums of the wearer, which device comprises a flexible backing frame including a central continuous web portion and spaced pairs of finger-like projections oppositely extending from the web portion and being substantially coextensive with the upper and lower gums of the wearer, a layer of soft pliable cushioning material mounted on the frame and covering at least one side of the frame that forms the gum-engaging side of the frame when in use, and fastening means for the cushioning layer engaging the backing frame for securing the cushioning layer in position on the backing frame.

5. A dental device adapted to be inserted into the vestibule of an oral cavity and to engage the teeth and gums of a wearer, which device comprises a flexible backing frame including a central continuous web portion covering and bridging the forward oral space between the upper and lower teeth and gums and lips of the wearer, spaced pairs of finger-like projections oppositely extending from the central web and extending around the upper and lower gums of the wearer between the gums and cheeks and being substantially coextensive with the gums, a layer of soft pliable cushioning material mounted on the frame and covering at least one side of the frame that forms the inner side of the frame when in use, and fastening means for securing the cushioning layer to the frame while enabling removal of the cushioning layer from the frame for cleaning purposes.

6. A dental device adapted to be inserted into the vestibule of an oral cavity and to engage the teeth and gums of a wearer, which device comprises a flexible frame including a central solid web portion and spaced pairs of substantially parallel finger-like projections oppositely extending from the said solid web as sides of deep indentations in the ends of the said frame, and a layer of soft pliable material mounted on the frame and covering completely at least one side of the frame, the layer of soft pliable material having a configuration similar to that of the frame but extending beyond the frame laterally and longitudinally thereof, and being adapted to engage both the upper and lower teeth and gums of a wearer and uniformly engaging and conforming to the upper and lower jaw portions of the vestibule of the wearer, the central solid web member forming an uninterrupted bridge spanning the frontal space between the upper and lower teeth and gums for preventing introduction of a finger into the mouth during wearing of the device, while the finger-like projections of the frame and of the covering material therefor retain the device in the mouth of the wearer by engagement thereof with the upper and lower teeth and gums of the wearer.

JOHN SAGE.
